VARIABLE TRANSLATION SPEED FEEDING
DEVICE FOR FABRICS AND THE LIKE

Julien Dungler, Thann, France

Application September 28, 1937, Serial No. 166,130
In France October 8, 1936

4 Claims. (Cl. 26—57)

The invention relates to the feeding or introducing, in machines, of all products of great length such as fabrics, paper, or like products of similar nature.

5 It concerns more particularly the feeding or introducing of the fabrics in textile machines such as, *inter alia* and in particular, tentering machines, drying drums, finishing machines, etc.

It is known that the feeding or supplying devices used at the present time have the drawback of being complicated and costly and of generally necessitating considerable and also costly transformations of the machines to which they are applied.

15 On the contrary, the device which is the object of the invention has the advantages of being extremely simple and not very costly to manufacture, of no longer necessitating the use of speed gear boxes, of enabling the speed of translation of the product to be varied at will during the actual operation of the machine while maintaining such operation constant, and also of being applicable to any machine without modifying the latter.

25 Said feeding device is characterized by the fact that it has in principle, and for each edge or selvedge of the product, a simple or multiple member which plays the dual part of speed changing device and of fabric feeding device, is driven by the machine to which the device is applied and has zones or sections of which the diameters progressively increase towards the said edge, in combination with a presser member mounted for longitudinal movement parallel with the axis of the feeding member, the fabric, paper or the like of which the edges pass between the feeding members and the presser members being thus fed at a linear speed of translation corresponding to the peripheral speed of the circumferences of the zones or sections of the feeding members with which the edges of the product are placed in contact by the presser members.

35 Embodiments of the invention are described hereinafter and illustrated diagrammatically in the accompanying drawings in which:

45 Fig. 1 is a front view of a device applied to the inlet of a pins tenter, for the purpose of overfeeding the machine with cloth.

Fig. 2 is an end elevation thereof.

50 Fig. 3 is a front view of a device constructed according to the same principle and placed at the inlet of an automatic clips tenter;

Fig. 4 is an end elevation thereof; and

Fig. 5 is a plan view of the same.

55 The device has a shaft 1 which is driven at con-

stant speed by the actual machine to which it is applied.

On said shaft 1 are mounted the feeding members comprising two conical sleeves 2 which are slidably keyed on said shaft so as to rotate in unison with same while being axially displaceable so as to modify the distance between them according to the width to be fed.

The speed of rotation of the shaft 1 is so chosen that the peripheral speed of the cones 2 at their medial portion corresponds to that of the tenter frame.

To each of the said cones there corresponds a presser member which is adapted to be longitudinally displaced while being held pressed against said cone.

With regard to the device of Figs. 1 and 2, this presser member comprises a roller 3 the rim of which is preferably covered with rubber to ensure a better adherence and consequently a better feed of the cloth. Said roller 3 is mounted at one end of an oscillating bell crank lever 4, the other end of which carries a counterweight 5. The fulcrum pins 6 of these levers 4, which are held in supports secured to those carrying the guide wheels of the tenter chains, enable the rollers 3 to be displaced by means of a thread formed on the pins 6 which can be rotated in their support by means of a knurled knob 7.

A roll 8 mounted parallel adjacent the roll 1 and adapted to receive the cloth, is driven direct by the said roll 1 by means, for example, of spur pinions 9, 9', the linear speed given said roll 8 being at least equal to or slightly greater than the peripheral speed of the large base of the cones 2, the speed of rotation of which is that of the roll 1. In the present case or application of this device as thus constructed to a pins tenter, circular brushes 10 which can rotate freely or be driven are provided and mounted above the pins 11 of the tenter frame which pass around the guide wheels 12, said brushes being arranged in such a manner that they penetrate on the one hand into the pins and that on the other hand they rub against the periphery of the roll 8.

40 This having been explained, the operation is as follows:

The cloth which starts from a guide roll 13, passes through a pair of selvedge guides 14 having an oscillating movement for example, and passes, 45 with its edges, round the cones 2 and the medial portion of the roll 1, over the top of the roll 8 and is engaged, by its selvedges, on the pins of the chains 11 by the circular brushes 10.

50 For a width of cloth of one meter, for example,

the chains at the entrance of the machine, are spaced about 60 centimeters apart, the cloth passing in full width over the upper guide roll 13, the two selvedge guiding devices 14 operating by repulsion and holding the two selvedges in an absolutely parallel position whereas the excess of cloth in width is repulsed into the medial part of the machine, forming a fold the amplitude of which will decrease or increase according to the differences of width that may occur in the course of a same piece of cloth, without for that reason destroying the parallelism of the selvedges.

The feeding cones 2, the small bases of which are facing each other, are arranged and adjusted along the roll 1 in such a manner that the selvedges pass around their periphery adjacent the large bases, and this has the further advantage of absorbing the possible slack of the said selvedges.

20 The presser rollers 3 are then placed in contact with the cloth which they press against the cones 2 owing to the action of the counterweights 5, or if necessary, under the action of springs.

25 Owing to this pressure of the rollers 3, the cloth adhering to the cones will be fed by its two edges, its linear speed of feed corresponding to the peripheral speed of the circumference of the portion of the cones against which the rollers 3 are bearing.

Consequently, if the diameter of the medial portion of the cones driven by the roll 1 which is actuated direct by the tentering machine, gives a peripheral speed corresponding to the linear speed of the cloth over the tenter frame, and the rollers 3 are placed on said medial portions, it will be readily understood that the speed of input of or of feeding of the cloth will correspond to that of the tentering machine and that in practice an intake will be obtained without tension but also without overfeed.

To obtain an overfeed of the cloth, it will suffice to move the rollers 3 more or less along the cones 2 by means of the screws 6 and the knurled knobs 7, towards the large base of the said cones, whereas to obtain a tensioned intake, it will suffice on the contrary to move the rollers 3 more or less towards the small base of the cones 2 in the desired proportion.

50 To facilitate the marking of the speeds, the surface of the cones 2 can, for example, be provided with parallel circular grooves spaced along the length of the cones, each groove giving a definite percentage of feed, apart from the control that it is possible to obtain between said grooves by displacing the cones along their roll 1 and/or the knobs 7 along the cones.

In the embodiment, shown in Figs. 3 to 5, of a device placed at the inlet of a clips tenter, the presser member comprises a belt 15 passing over rollers 16 of which the axles are mounted on a support 17. Said support 17 is tapped and mounted on the threaded part of a spindle 18 provided with a hand wheel 19; it is furthermore extended by an arm having a counterweight 20, this latter serving to press the belt 15 against the cone 2. By rotating the hand wheel 19, the support 17 is displaced, together with the belt 15 and the rollers 16, along the surface of the cone.

70 The spindle 18 rests in a bearing 21 fixed at the inlet of the tentering machine 22. If the inlets of the tentering machine are moved, the supports 17 move with them together with the

two cones 2, each of which is displaced by the fork 23 secured to the inlet of the tentering machine.

The spindle of the lower roller 16 is provided with a second roller 24 which drives a roll 28 through the instrumentality of a belt 25 having a tighten roller 26 provided with a counterweight 27. On the roll 28 rests an upper roll 29 having a counterweight 30.

The opening of the clips of the tenter frame is effected by means of superposed plates 31, one end of which penetrates deeply into the clips; these two plates 31 are spaced apart about 5 mm. and the cloth 32 slips in this space. Said plates 31 are arranged between the cones 2 and 15 the drawing rolls 28, 29.

The operation of the apparatus is as follows:

The cloth 32 is introduced into the tentering machine by automatic selvedge guiding devices 14 which can be adjusted so as to operate by repulsion; the selvedges are located for example at A and A'.

If the machine is started and the belts 15 are located for example in the middle of the length of the cones 2, the cloth 32 is introduced without tension but also without overfeed. If said belts 15 are moved outwards, the speed of introduction of the cloth increases relatively to the speed of the tentering machine. As the cloth which is drawn off by the rolls 28, 29 is conveyed into 30 the clips by slipping through the double plate 31, any danger of irregular intake is avoided.

Applicant has thus succeeded with this apparatus in giving creped fabrics up to 18% of overfeed, whereas for sateens it has been possible 35 to obtain 5% to 6% lengthwise shrinkage.

It is of course understood that without exceeding the spirit of the invention, changes, improvements and additions can be made and also the use of equivalent means can be contemplated. 40

I claim:

1. The device for feeding fabrics, paper and the like to machines, said device comprising a driven shaft, a separate conical sleeve for each side edge of the fabric, said sleeve being shiftable in the longitudinal direction of said shaft and rotatable therewith, the diameter of said conical sleeve increasing toward the adjacent end of said shaft, and a separate presser member for each sleeve, said member being movable in the longitudinal direction of said sleeve and pressing the side edge of the fabric against said sleeve, whereby the speed of the feeding of the fabric is adjustable without steps by shifting the presser member relatively to the sleeve. 55

2. The device for feeding fabrics, paper and the like to machines, said device comprising a driven shaft, a separate conical sleeve for each side edge of the fabric, said sleeve being shiftable in the longitudinal direction of said shaft and rotatable therewith, the diameter of said conical sleeve increasing toward the adjacent end of said shaft, guide rolls situated adjacent said sleeve, and a belt extending over said rolls, said rolls and said belt being movable in the longitudinal direction of said sleeve, said belt pressing the side edge of the fabric against said sleeve, whereby the speed of the feeding of the fabric is adjustable without steps by shifting said rolls and said belt relatively to the sleeve. 65

3. The device for feeding fabrics, paper and the like to machines, said device comprising a driven shaft, a separate conical sleeve for each side edge of the fabric, said sleeve being shiftable in the longitudinal direction of said shaft and 70

75

5 rotatable therewith, the diameter of said conical sleeve increasing toward the adjacent end of said shaft, a separate presser member for each sleeve, said member being movable in the longitudinal direction of said sleeve and pressing the side edge 10 of the fabric against said sleeve, whereby the speed of the feeding of the fabric is adjustable without steps by shifting the presser member relatively to the sleeve, rolls for drawing the fabric, and means operatively connecting said 15 rolls with said sleeve for driving said rolls.

4. The device for feeding fabrics, paper and the like to machines, said device comprising a driven shaft, a separate conical sleeve for each side edge of the fabric, said sleeve being shiftable

5 in the longitudinal direction of said shaft and rotatable therewith, the diameter of said conical sleeve increasing toward the adjacent end of said shaft, a separate presser member for each sleeve, said member being movable in the longitudinal direction of said sleeve and pressing the side edge of the fabric against said sleeve, whereby the speed of the feeding of the fabric is adjustable without steps by shifting the presser member relatively to the sleeve, rolls operatively connected with said sleeve for drawing the fabric, and superposed plates for opening the clips of a tenter frame, said plates being situated between said sleeve and said rolls.

JULIEN DUNGLER. 15
